UNITED STATES PATENT OFFICE

WALTER W. ZIEGLER, OF LAKEWOOD, OHIO, ASSIGNOR TO THE CLEVELAND HEATER COMPANY, OF CLEVELAND, OHIO, A CORPORATION OF OHIO

WATER HEATER

Original application filed July 20, 1926, Serial No. 123,690. Divided and this application filed April 21, 1928. Serial No. 271,762.

This invention relates to water heaters and in particular the base and burner assembly therefor.

This application is a division of copending application, Serial No. 123,690, which has matured into Patent No. 1,759,891, filed July 20, 1926, by Walter W. Ziegler, Loran F. Doen and Edmund J. Te Pas as joint inventors.

It is customary in water heaters of the usual type, in which a tank of water is heated by the flame from a gas burner positioned below water circulation elements in communication with the tank, to mount the burner upon the Bunsen or mixing tube by either a ground or a threaded joint.

When a ground joint is used the end of the Bunsen tube is finished smooth and slightly tapered and adapted to snugly fit into a bored out cylindrical extension of the burner. This arrangement of parts is open to the objection that upon removal and replacement of the burner a gas-tight fit may not be achieved on account of dirt or other foreign material lodging between the contacting portions of the Bunsen tube and burner.

In order to overcome this objection and still retain advantages of the ground joint, such as ease in removal and replacement of the burner for cleaning etc., heaters have been made in which the Bunsen tube and burner are provided with a threaded joint to insure at all times a gas-tight connection at this point.

Experience has shown that after a time the threaded joint becomes rusted and it is impossible to remove the burner from the Bunsen tube without the use of tools which cannot be manipulated in the limited space in the heater casing. In this case the heater base which carries the Bunsen tube and burner is removed from its casing and the burner is then removed from the Bunsen tube.

One of the objects of this invention is to provide a heater base in which the assembled burner and Bunsen tube can be quickly and easily installed or removed without disturbing the attachment of the base to the heater casing.

Another object of this invention is to provide an improved means of connecting the

Bunsen tube to the gas feed line. These and other objects will appear from the following detailed description and appended claims.

In the accompanying drawings forming a part of this specification are illustrated embodiments of the features of this invention in which: Fig. 1 is a side elevational view partly in section of a water heater with a section of its base removed and embodying features of this invention. Fig. 2 is a side elevational view of the Bunsen or mixing tube. Fig. 3 is a perspective view of the heater base member used in Fig. 1.

Referring to Fig. 1, the numeral 1, designates the casing of a heater having a heating coil 2 adapted to be connected at its extremities in the usual manner to the top and bottom of a boiler, so that there is a circulation of water through the coil and boiler when the burner is in operation. The burner 3 is mounted on a Bunsen or mixing tube 4 by means of a threaded joint.

Means comprising projecting lugs 5 and a collar 6 forming an integral part of the Bunsen tube cooperate with helical projections or ledges 7 in a central aperture 9 of the base 8 to securely and detachably hold the Bunsen tube in position in the heater base. A pair of diametrically opposed vertical slots 10 are provided for reception of the lugs 5 and to permit the insertion and removal of the Bunsen tube in the assembled heater base.

The heater base 8 is made in two pieces comprising the fixed element 11 and the removable element 12 shown in Fig. 3, and they are provided with skirted portions 13 and a recessed portion at 14 to form a drip collection and evaporation pan for the collection of condensate from the heating coils. A raised seat 15 having positioning lugs 16 is adapted to be detachably held in contact with the heater casing by rods or bolts passing through the holes 17 formed in the base.

Secondary combustion-supporting air inlets 18 are provided between the drip pan and the skirted edge of the base. In order to permit the insertion or removal of the burner and Bunsen tube in their assembled state, the removable segment 12 fits in a vertically walled space of a similar outline in the base

member 11. The removable segment 12 has vertical walls 19 and a recessed portion 14 constituting a drip collection and evaporation pan.

5 The removable section or segment 12 is of an irregular outline and is provided with a pair of fingers 24 which cooperate with the opening 25 in extensions 26 of the base member 11, to position and support the section 12.

10 At the central aperture 9 the contacting portions of the fixed and removable elements 11 and 12 are cut on an angle from the vertical as at 27 and 28 to further assist in properly locating the removable element 12 and to permit the fixed element 11 to wholly support the Bunsen tube when in its locked position as shown in Fig. 1. It is apparent from the foregoing description taken in connection with Figure 3, that the removable section 12 and the assembled burner head and mixing tube can be easily and readily removed and replaced without the use of any tools.

15 As a further means of facilitating the removal and replacement of the burner assembly, a combined union and spud holder 31 is screwed into the lower end of the Bunsen tube 4. The lower end of this union carries a gas cock 29 to control the flow of gas from a main fuel feed line to the burner. The male element of the union 31 is held from turning in the Bunsen tube by a locknut 33 which also serves to lock the air shutter 34 in position. The union nut 32 serves to hold the union together, and upon loosening it the Bunsen tube may be readily disconnected from the gas line, permitting the removal of the Bunsen tube with its associated burner from the heater base in the manner described.

20 Furthermore, it is to be understood that the particular forms of apparatus shown and described, and the particular procedure set forth, are presented for purposes of explanation and illustration and that the various modifications of said apparatus and procedure can be made without departing from my invention as defined in the appended claims.

I claim:

25 1. A base unit for a heater casing, having a longitudinally slotted central bore, helical supporting ledges formed about said bore and a Bunsen tube provided with a collar and projecting lugs adjacent said collar and adapted to be inserted and locked in said bore by said lugs, supporting ledges and collar.

30 2. In a gas burning appliance, a casing or jacket, a burner mixing tube, an apertured base secured to said casing for the reception and support of said tube, and a removable section forming a part of said base normally engaging the side of said tube adapted on its removal to provide an opening in the

side of said base for the withdrawal of said tube.

3. In a gas burning appliance, a casing or jacket, a burner mixing tube, a base member secured to said casing having a cut-away portion for the installation and reception of said tube, and a loosely carried closure member adapted to fit in cut-away portion of said base.

4. In a gas burning appliance, a casing or jacket, a gas burner, a vertically disposed conduit connected thereto, a burner supporting member carried by said casing having an opening for the reception of said conduit, and a removable section for said supporting member forming a side of the conduit receiving opening.

5. In a gas burning appliance, a casing or jacket, a gas burner, a vertically disposed conduit connected thereto, and a fixed and a removable section constituting a supporting base for said burner and providing an opening therebetween for reception of said conduit, said fixed section being secured to said casing.

6. A water heater comprising, a heater casing, a door for said casing, water circulating elements in said casing, an apertured burner supporting base secured to said casing, a gas burner and associated fuel supply conduit adapted to be supported in the aperture of said base, and a loosely carried member forming a part of said base adapted upon its removal to permit the unitary removal of said burner and conduit through the side of said base.

7. A water heater comprising, a heater casing, a door for said casing, water circulating elements in said casing, an apertured burner supporting drip pan secured to said casing, a gas burner and associated fuel supply conduit adapted to be supported in the aperture of said drip pan, and a loosely carried member forming a part of said base adapted upon its removal to permit the unitary removal of said burner and conduit through the side of said base.

8. The combination of a gas burner having a vertically arranged fuel supply conduit rigid therewith, a casing or jacket and a base therefor having fixed and removable sections defining a conduit receiving aperture therebetween to permit the installation of the burner in the center thereof through the opening formed by the removal of one of said base sections.

9. A burner support comprising, a base member having a fixed and a removable section defining an aperture therebetween, a burner supporting tube adapted to be loosely received in the aperture of said base, and cooperating means provided by said tube and base for rigidly securing said tube therein.

10. A burner support comprising, a base member having a fixed and a removable sec-

tion defining an aperture therebetween, a burner supporting tube adapted to be loosely received in the aperture of said base, and co-operating means provided by said tube and the removable section of said base to lock the removable section to the fixed section of said base.

11. A burner support comprising, a base member having a fixed and a removable section defining an aperture therebetween, a burner supporting tube adapted to be loosely received in the aperture of said base, and co-operating means provided by said tube and the sections of said base to rigidly secure said tube and removable section to the fixed section of said base.

12. A burner support comprising, a base member having a fixed and a removable section defining an aperture therebetween, sloping ledges formed on the sections of said base member adjacent said aperture, a burner supporting tube adapted to be loosely received in the aperture of said base, and laterally extending lugs and a flange formed on said tube adapted to rigidly hold the sections of said base therebetween upon said lugs engaging said ledges.

13. A drip pan for gas fired water heaters comprising, a fixed recessed section, a removable recessed section loosely supported thereon defining an aperture therebetween, and a burner supporting tube adapted to be vertically positioned in the aperture of said drip pan.

14. In a gas burning appliance, a casing or jacket, a gas burner having a vertically disposed tube connected thereto, a base member for said casing having a cut-away portion for installation and reception of tube of said burner, a closure member adapted for removable reception in the cut-away portion of said base member, and cooperating elements provided by said members to position and support said closure member.

45. In testimony whereof I affix my signature.
WALTER W. ZIEGLER.
